Specification of Letters Patent.

Patented Feb. 6, 1917.

Continuation of application Serial No. 374,280, filed May 17, 1907. This application filed August 2, 1911. Serial No. 642,009.

To all whom it may concern:

Be it known that we, CHARLES D. LANNING and STEPHEN C. DREW, citizens of the United States, and residents, respectively, 5 of Boston, county of Suffolk, and Brookline, county of Norfolk, State of Massachusetts, have invented an Improvement in Telephone-Circuit Arrangements, of which the following description, in connection 10 with the accompanying drawings, is a specification, like characters on the drawings representing like parts.

This invention relates to telephone circuit arrangements being particularly concerned with the relation of two voice current circuits inductively connected.

While it has broader and more extensive application for illustrative purposes, we have herein disclosed the invention as applied to a telephone circuit reinforcing arrangement of the kind disclosed in a prior application of Charles D. Lanning, one of 20 the applicants herein, wherein a repeater embodying a receiving element and a transmitting element controlled thereby are both serially related to a conductor forming part of a telephone line system.

We have found that such transformer losses and impairment of desired wave form 30 as are present in the transformer action of the induction coil embodied in the commercial telephone transmitting circuit arrangement (and which in substance is employed in most forms of telephone repeating, re-laying or reinforcing arrangements) become a marked disadvantage where the telephone current impressed upon the line by the original voice-actuated transmitter apparatus is again employed to energize or 40 control such repeating, relaying or reinforcing apparatus; the new current set up by such last mentioned apparatus being the result of an additional transformation action in which the transformation loss and 45 impairment of the wave form becomes cumulative with reference to the original loss and impairment in the original transmitter-transformer action. That is, the transformation loss in the repeater apparatus im- 50 pairs the accomplishment of the object desired to be attained by such apparatus which is the reinforcing of the line current, or the setting up of a new line current stronger than the original line current (as

the case may be); while the impairment of 55 the wave form still more materially operates to directly defeat the desired object in that the quality of the voice reproduction is impaired by this impairment of the wave form. We have found that by a different 60 connection of the usual telephone coil windings an improved result may be had through the reduction of transformation losses and the relieving of the transformer to a large extent from the magnetic leakage 65 and inductive choke resulting from the use of transformers or induction coils as ordinarily used.

In telephone transmission the transformer is practically universally though not 70 necessarily in the form of an induction coil or a transformer having a non-continuous ferric magnetic circuit. Such form is preferred because, with the high frequency and varying-value currents employed, hysteresis 75 losses are encountered with other forms of transformers resulting in and of themselves in transformer losses and other effects which impair voice current production and reproduction so that the ordinary induction 80 coil with the usual rectilinear or non-continuous core has been found to be the most efficient type of transformer apparatus for such telephonic use.

Such coils are in general wound with the 85 primary portion nearest the core and in cylindrical layers extending continuously along the core and with the secondary wound in cylindrical layers outside the primary though the secondary is sometimes 90 wound in sections, in the well known manner.

In these forms we have found that there is a clear loss of transformation efficiency 95 due to the fact that part of the flux set up by the primary through the core completes its circuit exteriorly of the core in the space between the primary and secondary windings, thus being ineffective as regards inductive effects upon the secondary. Moreover this portion of the flux acts with a distinct choking effect, that is, a self inductive effect, upon the primary; and thus acts to prevent completely responsive action of the primary with reference to the variations 105 impressed upon it.

To wholly or materially overcome or lessen these defects we have taken this coil

so constructed and have put both the usual primary and the usual secondary in series as the secondary winding, utilizing the usual coarse wire interior portion as a primary winding, speaking with reference to step-up transformers; similarly positioned and constructed windings being preferably used and reversely connected for step-down transformers. This, it will be seen, ~~10~~ furnishes an auto-transformer type of induction apparatus; but broadly and essentially and irrespective of the transformer type resulting from the circuiting of this usual induction coil in this manner, this circuiting ~~15~~ with step-up apparatus places that portion of the secondary which constitutes the primary within the outer limits of the primary winding and thereby renders the entire flux set up by the primary operative inductionally upon that portion at least of the secondary. With step-down apparatus it places the whole secondary within the outer limits of the primary. This wholly, or to a very great degree minimizes the ~~20~~ transformer loss resulting from coils or induction apparatus as ordinarily wound and employed in telephonic practice and makes the entire flux variation operative upon the secondary and wholly or substantially eliminates the self-inductive choking effect in the primary otherwise resulting from the leakage flux as above noted.

The problem of securing effective repeating, relaying or reinforcing action upon telephone lines has been one of great difficulty and has been one of slow solution, but we have found that with well constructed forms of telephone relays or repeaters (particularly when employed in such circuit arrangements as are disclosed in said application of Lanning above referred to or as are disclosed herein) a very marked improvement is had in efficiency of action by repeating, relaying or reinforcing apparatus when transformer construction and circuiting as described herein is employed, the peculiar efficiency of the same as applied to telephone circuits undoubtedly being due to the fact that the telephone voice current ~~40~~ is exceedingly complex, varying greatly both in frequency and in amperage. The voice current as originally impressed being of such slight strength the reduction of loss in transformer action both as regards strength ~~45~~ of action and accuracy of wave form reproduction is of vital importance.

It will be seen, therefore, that broadly our improvement consists in so constructing ~~50~~ transformers or induction apparatus and arranging the winding of such apparatus in telephonic use that the magnetic leakage losses and consequent impairment of efficiency resulting from the present forms of such apparatus employed in telephonic work ~~55~~ are largely eliminated. The principles of

our invention may, therefore, not only be applied to various forms of transformers or induction apparatus for telephonic purposes relating to repeating, relaying or reinforcing devices, but also to such transformer or ~~70~~ induction apparatus for use in combination with the usual voice-actuated transmitter.

The precise form that we have shown herein (that is, an auto-transformer) has particular advantages in that the entire ~~75~~ winding of the transformer apparatus can be placed in series with the line and thus a complete metallic circuit afforded for the voice current, which circuit has in series with it the entire winding of the ~~80~~ transformer apparatus. This results in bringing into the line as parts of a total inductance-creating element thereof all the various inductance-creating elements of the ~~85~~ transformers associated therewith; and, in connection with the particular form of circuiting which we have shown herein for illustrative purposes (embodying a telephone reinforcing circuit arrangement) creates a line condition which may be called "unitary." ~~90~~ That is, whatever the length of the line may be from terminal station to terminal station, dependent upon what terminal connections are using the line, the latter with all the inductance creating elements embodied in ~~95~~ the transmitting, receiving and reinforcing stations is a unit, obviating the necessity for artificially balancing one section of the circuit against another or balancing against each other the line and the reinforcing ~~100~~ circuit.

We have illustrated our invention herein in connection with a telephone circuit having terminal stations and an intermediate reinforcing circuit arrangement serially related to the line. ~~105~~

The invention will be best understood by reference to the following description when taken in connection with the accompanying illustration of one specific embodiment ~~110~~ thereof while its scope will be more particularly pointed out in the appended claims.

In the drawings Figure 1 represents a telephone line with its terminal stations and two intermediate reinforcing stations each ~~115~~ of the latter having a transformer constructed and connected in accordance with our inventions.

Fig. 2 is similar in all respects to Fig. 1 except that the receiving elements of the ~~120~~ reinforcing stations are inductively connected to the line.

Fig. 3 represents a similar telephone line with its terminal station and two intermediate reinforcing stations with the primary ~~125~~ portion of the reinforcing transformers having a split or divided connection to the line.

Fig. 4 is similar in all respects to Fig. 3 except that the receiving elements of the ~~130~~ re-

inforcing arrangements are inductively connected to the line.

Fig. 5 is a similar diagram of the telephone line with its terminal stations, having two intermediate reinforcing arrangements each embodying a transformer, one of the reinforcing arrangements being connected to one side of the main line and the other to the opposite side of the main line.

Fig. 6 is a modified circuit arrangement showing a portion of the telephone line, an intermediate station with two reinforcing arrangements thereat related to the main line, and also a speaking and listening station connected to the line at said intermediate point.

Fig. 7 shows a telephone line with terminal central energy stations, having two intermediate reinforcing arrangements connected to the line, each reinforcing arrangement having both its receiving and transmitting elements connected to the line through a transformer constructed and connected in accordance with our invention, the connections from the respective central energy stations to the terminal speaking and listening stations, and the instruments and connections of the latter being omitted.

Fig. 8 is a sectional view of a transformer in the form of an induction coil constructed and connected in accordance with our invention.

Referring to the figures in detail it will be seen that there are certain features in common with reference to all the circuit illustrations, that is, Figs. 1 to 7 inclusive. That is, in all said figures the current reinforcing devices embody a receiving element as the magnet 8, in all such figures, there being connected therewith in Figs. 2, 4 6 and 7, a receiving transformer 15; and further embodying a transmitting element operated and controlled by said receiving element as the microphone 9 controlling the circuit energized by the local supply 10 in series with the primary of the transmitting transformer 12.

In all said figures also it will be seen that each of the said receiving elements and transmitting elements are connected in series to a conductor and both of them to the same conductor, forming part of the line system; said conductor in the forms illustrated being one of the main line conductors. That is, having reference to the action and reaction between the line system and the reinforcing arrangement, the latter is in series relation to a single undivided conductor, this conductor in the special form shown being as stated one of the main line conductors. The general advantages of this construction and circuiting are fully set out in said application of said Lanning, being in brief that all weakening and conflict of currents is avoided through the elimination of recipro-

cally arranged main circuit portions and the elimination of forms including bridge conductors with the one portion of the reinforcing arrangement related to the bridge and another portion to another bridge or to a portion of the circuit exterior to the bridge.

By this arrangement as disclosed in said application the reinforcing arrangement is acted upon by and reacts upon a single and the same conductor. Further in this form of connection and in the special form shown herein and in said other application referred to the reinforcing arrangements are in series relation to the main line conductor so that the total original line energy is conserved and built up by the reinforcing action without any weakening of the line effects at either terminal station by the interposition of bridge circuits or other form of split or divided main circuits therebetween.

In all these figures the transmitter elements of the reinforcing arrangement, whether the receiving transformer or the transmitting transformer thereof, are preferably constructed and connected in the general manner described in Fig. 8; and are so shown diagrammatically in Fig. 7.

This transformer is built in the usual way as an induction coil (Fig. 8) with the primary winding 32 of relatively coarse wire and desired number of turns and ohmic resistance continuously surrounding the core 30 and placed next thereto and with the balance of the winding 33, composed of relatively fine wire of the desired number of turns and ohmic resistance, surrounding the primary; this fine wire portion may be in a single compact body of turns as shown, or in section form. The whole winding is connected in series, being wound in one direction, the entire winding being used as a secondary and the coarse wire portion as a primary, in step-up work.

Preferably when employed as a step-down transformer, as in connection with the receiving elements of the reinforcing stations in Fig. 7, the transformer is wound in the same way and the entire winding used as a primary with the coarse wire winding used as a secondary.

Whatever the type of the transformer, that is, whether induction coil or other form we embody the principle illustrated in this construction, that is, so arrange the windings and so connect them that a portion at least of the step-up transformer type secondary winding is within the outer radial limits of the primary winding; that is, lies within the space surrounding the core the limits of which space inclose the primary winding. In this manner, as we have pointed out, the leakage loss resulting from passage of flux between the primary and secondary windings is substantially or wholly eliminated; and the result of this

elimination is not only to increase the strength of the induction action upon the secondary but to relieve the primary of the choking effect otherwise resulting from this 5 leakage flux. This construction we find to be of great advantage in all transformer combinations with telephone lines and it may be used as well with the transformers constituting part of the voice-actuated transmitter stations as with the receiving and transmitting elements of repeating, relaying or reinforcing stations where transformers are used.

With this explanation of the general circuit arrangements and the construction in connection with the transformer the detail figures illustrating the general circuit arrangements will be clearly understood.

In Fig. 1 A and B designate in general 20 the terminal stations and 1 and 2 the main line connecting the same. Two reinforcing stations are shown both of which are connected to the conductor forming part of the main line system in the same manner 25 and a description of one will suffice. The main line is in series with the electro magnet 8 which diagrammatically represents any of the usual type of initially energized telephonic receiving magnets. The line then 30 passes in series through the condenser 14 and the whole winding of the transformer 12 constructed and connected in detail as shown in Fig. 8 and as above described. 35 9 represents diagrammatically any of the usual forms of variable resistance microphone having its vibratory electrode connected to an armature in the field of the receiving magnet 8, said microphone having in series the primary portion of the transformer 12 and a local source of energy 10. By this means voice-caused currents impressed upon the line by either of the terminal stations energize the magnet 8 which in turn by its effect upon the vibratory electrode of the microphone 9 sets up current 45 variations in the local circuit in series with the transformer primary again inducing alternating currents harmonious with the original voice-caused currents which are 50 added to the original main line current.

It will thus be seen that the new alternating current set up by the reinforcing arrangement is caused by the series action of a conductor forming part of the line system and again sets up by series action upon said conductor another and harmonious alternating current. It is obvious, of course, that the connections of the reinforcing arrangement of the line should be such that the new current set up by the reinforcing instruments shall be harmonious in phase with the alternating current originally impressed upon the line by the terminal station. If this is done and synchronism of the two current effects maintained, cumulative rein-

forcement of the voice current on the line will be had, the full strength of the original current being retained on the line subject only to the slight energy loss required to operate the reinforcing instrument.

The construction shown wherein the reinforcing instruments are serially related to one of the main line conductors is the preferable form, although other circuit relations of the receiving and transmitting elements 70 might be employed; but the connections shown in Fig. 1 illustrate in general the preferable form of connection, avoiding as it does the weakening of the line current effects by bridging or other form of split 75 circuit arrangement.

This general form is disclosed in the said application of said Lanning above referred to but in the form illustrated in the drawings by reason of the improved construction and 80 connection of the transformer an added effect is had. It will be seen that the line is in unbroken metallic connection through both the receiving and transmitting element 85 of the reinforcing station and it will further be seen that the total inductional effect of the transformer 12 is delivered onto the main line, the inductional choking effect that would otherwise become operative upon the insulated primary of the transformer being 90 obviated; this inductive choking effect arising principally, it will be clear, upon that portion of the primary that composes the transformer winding, and which therefore 95 is in series with the line.

Due to the relation of the primary and secondary portions of the transformer and connections herewith the direct and alternating currents normally tend to be confined to their respective portions, but a condenser 100 may be interposed as at 14 to check direct current flow in the conductor related to the main line system. As to alternating current flow in the transformer primary this is substantially negligible and moreover we have 105 found that variable resistance microphones of the usual type and particularly those of the granular contact type offer in and of themselves a very heavy resistance or impedance to alternating current flow, this being caused probably by the multiple current paths through such granular contact microphones and the inductional effects of the various current portions therethrough upon 110 each other.

In Fig. 2 the connections are the same as in Fig. 1 except that a step-down transformer is shown to inductionally connect the receiving elements of each reinforcing arrangement to the line, as 15 in said figure.

In Fig. 3 the connections of the reinforcing arrangements and the transformers thereof to the line are the same as in Fig. 1 except that the main line is tapped out of the center of the primary portion of the 125 130

transformer winding and, in addition to the connection of the local direct current circuit to the transformer primary, an independent loop circuit is formed around the primary portion through 17 and the condenser 18 whereby any inductional effect reacting upon the primary portion of the transformer may be balanced by opposed induction effects upon the portions thereof, and at the same time the short circuiting of the direct current flow through such loop circuit prevented.

In Fig. 4 the connections of the reinforcing arrangements and their transformers to the line are the same as in Fig. 3, the receiving elements of the transformer being, however, inductionally connected to the line by the transformers 15 and as in Fig. 2.

In Fig. 5 two reinforcer arrangements are shown, each connected independently to one side of the main line circuit in the same manner as is shown for the connection of the reinforcing arrangement in Fig. 3. By this means reinforcer arrangements are symmetrically placed on the main line circuit so that reinforcing action is symmetrically had thereon, having reference to the length of main line extending between the terminal stations and alternating current action thereon. It will be understood, of course, that in place of the precise connections shown in Fig. 5 for the reinforcing connections any of the connections herein shown in any of the figures may be substituted.

In Fig. 6 two reinforcing arrangements with their transformers connected as described are shown connected to one side of the main line 1 and 2 at an intermediate point, symmetrically related to a speaking and listening station comprising the transmitter 4 and receiver 3 and transmitting induction coil 6.

In Fig. 7 in place of the local energy terminal stations illustrated in Figs. 1, 2, 3, 4 and 5 there is illustrated a line between two central energy supply stations B, B', the local station connection from such central energy station supplies 20, 20' and 21, 21' respectively being indicated but the other connections to the local station instruments being omitted. In this form in connection with the main line 1, 1 between the terminal central energy stations are shown two reinforcing arrangements with their transformers, one being connected to one side of the main line and the other to the opposite side as illustrated in Fig. 5. Further in this form the connections of the receiving elements of each of the reinforcer arrangements are shown as step-down auto-transformer connections, the transformer being wound and connected as a step-down transformer in accordance with the principles of our invention and as above described.

Fig. 8 has been described in detail above.

The circuit arrangement as herein shown in its detail form for illustrative purposes is, as above stated, an improvement on that disclosed in said co-pending application of 70 Lanning.

In the said co-pending application an explanation is made of the causes of the "reaction", so called, on telephone lines. As therein explained, a reinforcing instrument related to the line or a conductor in the line system by pure serial circuiting is in what may be termed a "unit" relation to the line with no reciprocally arranged or split line sections; and if properly circuited so as to 75 secure phase harmony of the original line current and the reinforcing current, and if further so designed as to minimize or eliminate mechanical lag or inertia and maintain synchronism, a unitary action of the whole telephone line, including the reinforcing circuit, is had, eliminating "reaction". In other words, synchronism and phase harmony are established and cumulative reinforcing action had.

By the circuit herein disclosed it will be seen certain improvements are secured tending toward greater efficiency. The induction coil or transformer as specifically illustrated is so circuited as to be in action obviously an auto-transformer. Further, the connections of the line to the reinforcing instrument, as related to the intermediate connections of the reinforcing system, are preferably made not only so that the primary and secondary portions of the reinforcing induction coil are connected so as to have a similar magnetizing or inductive effect (i. e., as an auto-transformer) but also so that this inductive effect is harmonious (in all alternate current telephony) 95 with the phase of the original transmitter-caused current. Since the induced current effects in both portions of the repeater transformer are harmonious or similar in phase, 100 and since the self-induced current in the primary portion of the repeater transformer is opposed in polarity to the change of current flow of the direct current therein, it results that preferably the voice-caused current and the total repeater or reinforcer-caused current are harmonious in phase and thus cumulative in effect but opposed to the 105 change of direct current flow in the primary of the repeater.

Our investigations show that as a result of this system of circuiting, the self-induced current of the reinforcer transformer primary winding is delivered on to the main line; and not only delivered onto the main 110 line but withdrawn from that portion of the reinforcer primary through the local battery and the reinforcer current-varying device. The latter elements are, therefore, relieved 115 of the choking effects of this self-induced 120 current.

current. This is of great benefit in telephone coils because of the fact that the ratio of windings between the primary and secondary in such coils usually is relatively low; ⁵ i. e., the number of turns in the primary is relatively large and hence the self-induction is large.

Moreover, when using alternating currents on the line, as is practically universal, a ¹⁰ device may be interposed either in the alternating current sections or the direct current sections or both to check the flow in the alternating current section of any leakage from the direct current looped sections, or, ¹⁵ conversely, to partially or wholly check the flow of leakage of alternating currents in the direct current section. We have illustrated, for instance, a condenser in the alternating current sections in looped relation to the ²⁰ reinforcer direct current sections to check any leakage of direct current from the latter into the former. In the same way an asymmetric or unilateral element may be interposed in the direct current sections, so ²⁵ that the leakage flow of one phase of alternating current therein, if such exists, may be checked; or a choke coil of low ohmic resistance but heavy inductance may similarly be interposed in said direct current ³⁰ conductors.

With reference to the unitary character of the circuiting therein pointed out, the circuit herein disclosed accomplishes a further step, for it will be seen that the ³⁵ whole main line, including the original transmitter induction coil secondary and the receiving and transmitting elements of the reinforcing instrument are in series connection. In this way the capacity and self-induction elements of the line and of the ⁴⁰ reinforcing system make up a unit element; that is, whatever the line length may be or however the length of line from the reinforcing station to terminal station may ⁴⁵ relatively vary these are qualities of one circuit of which the capacity and inductance of the transmitting coil, of the line, and of the elements of the reinforcing instrument are merely component parts;—and are not elements of differently constituted and varying ⁵⁰ circuits and hence requiring adjustable balancing arrangements.

We have herein shown the repeater transmitter transformer as an auto-transformer ⁵⁵ having only a portion of its winding in the primary. This it will be clearly apparent to those skilled in the art is the preferable form particularly in telephonic work, as the ohmic resistance of the primary is thus reduced; this affecting the direct current flow therein, and thereby affecting the effective action of the variable resistance device, which action has relation to the total resistance of said primary; and this arrangement ⁶⁰ of course gives any desired voltage increase. ⁶⁵

But obviously the whole winding of the repeater transformer could be placed in series as a primary and yet give a reinforcing effect.

It will be understood that some of the drawings are meant to show broadly telephone circuits in which there is no direct current flow in the main line at the repeating station; which is the condition generally speaking of telephone circuits that are not ⁷⁰ of the central energy type and of most circuits that are of the central energy type. Where the circuit is of a central energy type necessarily including (i. e. operatively requiring) a direct current flow through all ⁷⁵ portions of the main line obviously the condensers in the line would be omitted as might be appropriate; and as already pointed out in the specification the difference of potential across the two connections of ⁸⁰ the repeater loop circuits to the main line is such that the main line flow through the loop circuit would be substantially negligible; while reversely the resistance of the main line considered as a loop of the repeating ⁸⁵ circuits will be relatively so great that the flow of current designed to pass only through the loop circuit will be substantially negligible in the main line. ⁹⁰

Wherever in the claims the phrase "magnetically independent" is used as applying to the elements of the reinforcing arrangement we mean thereby electro-magnetic elements having operatively independent windings;—which in general means structurally ⁹⁵ separate magnetic cores, or operatively separated windings, so that energization of each such coil will directly affect only the desired or related instrument or portion thereof. ¹⁰⁰

In the sub-joined claims where we use the phrase "voice-current circuit" we refer to a circuit in a telephone system wherein varying currents flow, the same being designed to correspond in wave form with the ¹⁰⁵ complex form of wave set up by the voice; as distinguished from ordinary current wave forms such as are used in other branches of alternating current transmission; the latter, of course, being of constant repeated form ¹¹⁰ and a compound of simple alternations, whereas the former is not only a compound of main alternations and of alternations of variations impressed thereon (corresponding to the dominant tones and over-tones in ¹¹⁵ the voice) but varies constantly in frequency, as following the voice pitch, and in amperage, as following the voice energy. In the claims, therefore, it is this character of circuit, designed to carry this complex current form, and to be related inductionally ¹²⁰ for transference of this wave form, which is designated "voice-current circuit."

Without limiting ourselves, therefore, to the precise forms of apparatus as shown in ¹²⁵ ¹³⁰

the drawings which are employed merely for illustrative purposes what we desire to claim broadly as our invention is:

1. In a telephone system in combination with the main line and its terminal instrumentalities, a voice-current-energized conductor in said system and a voice-current-repeating device, said conductor and device being inductionally connected by a transformer, said transformer having a portion of its windings in series with said conductor and a portion in series with the circuit controlled by said device, the said transformer being so wound and constructed that a portion at least of the secondary winding lies within the space limited by the outer radial limits of the primary winding; the said second mentioned portion of said winding having fixed connections to a direct-current-energized circuit with a current-varying device therein operatively controlled by said voice-current-energized conductor; the said repeating device being connected to said system solely for series actuation thereby.
2. In a telephone system in combination with the main line and its terminal instrumentalities, a voice-current-energized conductor in said system and a voice-current repeating device, said conductor and device being inductionally connected by a transformer, said transformer having its winding composed of an interior portion of coarse wire and an exterior portion of fine wire and having its whole winding in series with said conductor and a portion in series with another circuit related to said repeating device.
3. In combination with a telephone main line system and its terminal instrumentalities, a line-actuated voice-current repeater arrangement comprising a receiving element and a transmitting element operated thereby, said transmitting element being inductionally connected to said line system by a transformer; said transformer having the interior portion of windings composed of coarse wire and the balance thereof of relatively fine wire and having its whole winding in series with the line, and said coarse wire portion in series with the related repeater device.
4. In combination with a telephone line system a voice-current reinforcer arrangement actuated by a voice-current energized conductor in said system and serially related to said conductor and operably related serially only to said conductor, said reinforcer comprising a receiving element and a transmitting element operated thereby and said transmitting element being inductionally connected to said conductor by a transformer; said transformer having its winding composed of an interior portion of coarse wire and an exterior portion of rela-

tively fine wire and having its whole winding in series with said conductor and said coarse wire portion in series with the related repeater devices.

5. In a telephone system, the combination of a station provided with transmitting and receiving instruments, a metallic circuit connecting the same with another station, a local reinforcing circuit operably related to but one of the sides of said metallic circuit and provided with a battery and a varying resistance medium, in said reinforcing circuit, an induction coil energized by the current undulations of said reinforcing circuit, the windings of said coil being in series with one another and the said side of the metallic circuit and an electromagnet operatively connected with the main line for actuating said resistance medium.

6. In a telephone system, a main line and means for generating current undulations therein, an electromagnet, in series relation to said line, and a repeating circuit containing a source of electrical energy and a varying resistance medium, the latter operatively related to and actuated by said electromagnet, and an induction coil, the windings of which are in series with said line, the said electro-magnet and said induction coil being magnetically independent of each other.

7. In a telephone system, a main circuit provided with means for current undulations therein and an electromagnet, an induction coil with its whole winding in series with said line, and a local circuit containing a portion of the winding of said induction coil, a source of electrical energy and a varying resistance medium, actuated by said electromagnet, and a condenser in said main circuit, whereby current undulations harmonious to those produced by said current generating means are transmitted from said local circuit to said main circuit.

8. In a telephone system, the combination with separated stations, of a main line connecting said stations means for producing current undulations therein, and a local circuit in repeating and reinforcing relation to said line, provided with an induction coil having its windings in series with said line, and means actuated by the current undulations of said main line for producing in said local circuit and transmitting to said line, through the action of said induction coil, current undulations harmonious to the original undulations thereof, the said induction coil being magnetically independent of the controlling means for said local circuit as actuated by said main line.

9. In a telephone system, the combination with a main line circuit, of means serially related to but one side of said circuit for reinforcing the energy undulations thereof,

- said means including an induction coil having a split primary with its branches serially connected and in series with the secondary thereof and said main line circuit.
- 5 10. A system for the transmission of electrical energy comprising a main line, means for energizing said circuit, a repeating circuit connected with said main line, means serially associated with the said main line 65
10 and controlled by the current variations thereof for producing corresponding current variations in said repeating circuit, and means serially associated with the repeating circuit and said current-variation-producing 70
15 means for reinforcing the energy passing through the latter, the said means serially associated with the said main line and the said means serially associated with the repeating circuit being magnetically independent of each other. 75
- 10 11. A system for the transmission of electrical energy comprising a main line metallic circuit, means for energizing said circuit, a repeating circuit connected with said 80
25 main line metallic circuit, means serially associated with said main line metallic circuit and controlled by the current variations thereof for producing corresponding current variations in said repeating circuit, and 85
30 means serially associated with the repeating circuit and said current-variation-producing means for reinforcing the energy of the main line circuit passing through the latter. 90
12. A system for the transmission of electrical energy, comprising a main line circuit, means including a source of electrical energy for producing current undulations therein, an operatively connected repeating circuit, means comprising an electromagnet 95
35 energized by the current undulations of said main line circuit for causing corresponding current undulations in said repeating circuit, and means including an induction coil 100
40 connected with said repeating circuit and having its primary and secondary windings 105
45 in series with one another and said main line for transmitting to the main circuit the current undulations of said repeating circuit. 110
13. A system for the transmission of telephone currents comprising a main line circuit, means for producing telephonic current undulations therein, a loop circuit having its terminals connected to one side of said main line circuit and provided with a 115
50 current varying device, an induction coil having primary and secondary windings in series one with another and said main line, one of said windings being in series with the current varying device of said loop circuit, 120
55 and electromagnetic means serially related to and energized by the current producing means of said main line circuit for operating said current varying device to produce current variations corresponding to those of 125
60 the main line in said loop circuit and 65 through the inductive action of induction coil to transmit the same to said main line circuit.
14. In a telephone system, a main line, means for producing current undulations 70
therein, a repeating circuit associated therewith having an independent source of electrical energy and a current varying device actuated by the current undulations of the main line, and an induction coil provided 75
with a split primary and a secondary winding in series relation to said main line. 80
15. In a telephone system, a main line, means for producing current undulations therein, repeating circuit associated therewith having an independent source of electrical energy and a current varying device actuated by the current undulations of the main line, and an induction coil provided 85
with a split primary and a secondary winding in series relation to said main line, said main line having a condenser for shutting out the battery current of the repeating circuit. 90
16. In a telephone system, the combination 90
of a main line circuit extending between separated stations, of means for producing current undulations therein and means comprising an electromagnet 8 in series relation with one side of the main circuit, and 95
a repeating circuit comprising a current varying medium 9 actuated by said electromagnet, a battery 10 and an induction coil 12, the windings of which are in series with the same side of said main circuit, for transmitting thereto, current undulations proportional and harmonious to the original current undulations therein, said induction coil having a split primary with its branches in series with one another and with the 100
secondary winding thereof and connected intermediate its ends at the branching point 105
thereof to said line. 110
17. In a telephonic reinforcing circuit, the combination with the main line speaking 110
circuit and its terminal instruments, of a local circuit, a source of electrical energy therefor, means serially related to the main line and adapted to impress on said local 115
circuit current variations harmonious with the original voice-caused current influences impressed on the main line circuit, and means also serially related to said main line circuit for producing in the latter current influences harmonious with said current variations of said local circuit, the first and second mentioned means being magnetically independent of each other. 120
18. In a telephonic reënforcing circuit, the combination with the main line speaking circuit 125
and its terminal instruments, of a local circuit, a source of electrical energy therefor, means serially related to the main line and

adapted to impress on said local circuit current-variations harmonious with the original voice-caused influences impressed on the main line, a local induction coil with its 5 primary and secondary in series with the said main line and one another.

19. In a telephonic reinforcing circuit, the combination with the main line speaking circuit and its terminal instruments, of a local 10 circuit, a source of electrical energy therefor, means serially related to the main line and adapted to impress on said local circuit current-variations harmonious with the original voice-caused influence impressed on the 15 main line and a local induction coil with its primary in balance split series with its secondary and with the said main line.

20. In a telephonic reinforcing circuit, the combination with the main line speaking circuit and its terminal instruments, of a local circuit, a source of electrical energy therefor, means serially related to the main line and adapted to impress on said local circuit current-variations harmonious with the original 25 voice-caused influences impressed on the main line, a local induction coil with its primary and secondary in series with the said main line and one another, and a con-

denser interposed in the said main line exterior to the said primary and secondary. 30

21. In a system for the transmission of electrical energy, a transmitting and receiving device, a continuous circuit between said devices, means for producing current undulations therein, means energized by said current undulations and in series relation with the main circuit for reimpresing upon the latter current undulations harmonious with those impressed by said current undulation-producing means and means for controlling 35 the effective lag of said reimpresing means.

22. In a telephone system, a sending and receiving station, an auto-transformer and an intermediate voice-current repeater and reinforcing circuit arrangement having connections with the line circuit through said auto-transformer. 40 45

In testimony whereof, we have signed our names to this specification, in the presence of two subscribing witnesses.

CHARLES D. LANNING.
STEPHEN C. DREW.
